UNITED STATES PATENT OFFICE.

OZRO N. WISWELL, OF LOS ANGELES, CALIFORNIA, ASSIGNOR TO SWINGSPOUT MEASURE CO., A CORPORATION OF CALIFORNIA.

SWINGSPOUT POURING DEVICE.

Application filed February 21, 1923. Serial No. 620,334.

This invention relates to pouring devices which may be used on packages and containers in which liquid substances are contained.

5 It is a principal object of my invention to provide a swingspout which may be mounted upon a container, this swingspout being equipped with a valve which is adapted to be opened and thus to permit a 10 free flow of oil when the spout is swung in pouring position and which is adapted to close so as to prevent the escape of oil from the container when the spout is in retracted position.

15 It is further the object of my invention to provide a swingspout of this character which when swung into pouring position will extend diagonally from the top of the container so that a proper pouring angle 20 is derived, and which when swung into closed position rests parallel to the top of the container.

25 The specific advantages of my invention and further objects thereof will be made evident hereinafter.

Referring to the drawing which is for illustrative purposes only,

Fig. 1 is a perspective view showing a form of my invention in pouring position 30 upon a container.

Fig. 2 is a fragmentary longitudinal vertical section through the pouring device in pouring position and through a portion of the container upon which the device is 35 mounted.

Fig. 3 is a fragmentary end view taken as indicated by the arrow 3 in Fig. 1, showing the shell of the pouring device previous to the placing of the cup member thereon.

40 Fig. 4 is a diagrammatic view of the conical shell member employed.

As shown in Fig. 2 of the drawing my invention provides a frusto-conical shell 11 which is stamped from sheet metal and has 45 formed therewith an outwardly extending flange 12 and a downwardly extending lip 13 formed on the periphery of the flange 12. As diagrammatically shown in Fig. 4, the member 11 is first stamped to the shape shown in full lines, the frusto-conical portion thereof being disposed perpendicular to the flange 12. The frusto-conical portion is then twisted so as to assume the position indicated by the dotted lines in this figure 50 and so that the axis A—A of the frusto-

conical portion is disposed at an angle to the flange portion 12 of the member 11. When the frusto-conical member 11 is placed upon the top 14 of the container 15, the 60 downwardly extending flange 13 thereof extends into the annular channel 17 formed in the top of the container and may be soldered in place. The shell 11 is so positioned on the container top 14 that the axis A—A is at an angle to the top 14, in the lateral aspect as shown in Fig. 2; while in frontal aspect the axis A—A of the shell is parallel 65 to the longitudinal plane of extension of the device, but is disposed diagonally with respect to the lateral plane of extension of the 70 container 15. The longitudinal plane of extension will be recognized to be any plane which is parallel to the two side walls 16 of the container 15 and the lateral plane of extension may be any plane which extends 75 parallel to the end walls 18 of the container.

As shown in Fig. 3 the cone 11 has an upwardly expressed tip 19 formed therein and has an opening 20 formed in the front thereof. A frusto-conical cup 22 is provided 80 which is of substantially the same size as the frusto-conical shell 11 and has a cylindrical and slightly converging spout 23 mounted thereupon. The cup 22 has a hole 85 24 formed in the end thereof which fits down over the tip 19 of the shell 11, thus allowing a portion of the tip to project beyond the end wall 25 of the cup. When the cup has been thus placed, the tip 19 is riveted down 90 as shown at 27 in Fig. 2 so that it flanges over the end wall 25 and exerts a downward pressure thereupon for holding the cup 22 95 pressurably upon the cone 11. The pouring spout 23 is mounted at an angle to the axis of rotation of the spout and cup 22 upon the shell 11, which axis of rotation is also represented by A—A. It will be perceived that the axis B—B slopes upwardly with respect to the axis A—A so that when the spout 23

is in pouring position, it slopes outwardly 100 and diagonally upwardly with respect to the container, and being thus diagonally disposed contributes considerably to the facility with which liquids may be poured from the container. When the spout 23 is swung 105 into closed position as indicated by the dotted lines 30 in Figs. 1 and 2, the axis B—B is disposed substantially parallel to the plane of the top 14, and when in this position the valve formed between the frusto- 110

conical shell 11 and the cup 22 is closed, thus preventing flow of liquid from the container.

From the foregoing, it will be recognized that by mounting the frusto-conical shell 11 upon the container in such a manner that the axis thereof is disposed parallel to the longitudinal plane of extension of the container, the axis of rotation of the pouring spout will revolve through a circular plane having its highest point directly forward from the container and its lowest point over the top of the container; and that by sloping the spout upwardly with respect to the axis of rotation, it may be caused to assume a position substantially parallel to the top of the container when disposed in closed position.

I claim as my invention:

1. In a swingspout pouring device for a container, the combination of: a shell adapted to be secured to the top of a container; an inverted cup rotatably mounted on said shell, and pressurably held thereagainst; and a spout extending from said cup and secured against rotation relative thereto, the axis of rotation of said cup, when mounted on a container, lying in a vertical plane and in a plane which is at an angle to a horizontal plane, the axis of rotation of said cup being adapted to be so positioned relative to said container and is so correlated with the axis of said spout that the axis of said spout slopes upwardly from a horizontal plane when the spout is in pouring position, and lies substantially in a horizontal plane when the spout is turned through 180° from its pouring position.

2. The combination specified in claim 1, in which said shell and said cup are frusto-conical, in combination with means for holding said cup pressurably on said shell.

3. The combination specified in claim 1, in which said shell and said cup are frusto-conical; means for holding said cup pressurably on said shell, said means comprising a tip expressed from the top wall of said shell, projected through an aperture in said cup and riveted down on the outside of said cup.

4. In a swingspout pouring device for a container, the combination of: a shell adapted to be secured to the top of a container; an inverted cup rotatably mounted on said shell; and a spout extending from said cup and secured against rotation relative thereto, the axis of rotation of said cup, when mounted on a container, lying in a vertical plane and in a plane which is at an angle to a horizontal plane, the axis of rotation of said cup being adapted to be so positioned relative to said container and is so correlated with the axis of said spout that the axis of

said spout slopes upwardly from a horizontal plane when the spout is in pouring position, and lies substantially in a horizontal plane when the spout is turned through 180° from its pouring position.

5. In a swingspout pouring device for a container: a frusto-conical boss secured to the top of said container so that the axis of said boss inclines upwardly toward the central axis of said container, there being an opening in the frusto-conical surface of said boss communicating with the interior of said container; an inverted cup fitting upon said boss and having an opening registerable with said boss opening by the rotation of said cup on said boss; and a spout provided upon said cup communicating with said cup opening, the axis of said spout being inclined upwardly at an acute angle with the axis of said boss.

6. In a swingspout pouring device for a container: a frusto-conical boss secured to the top of said container so that the axis of said boss inclines upwardly toward and when extended intersects the extended central vertical axis of said container, there being an opening in the frusto-conical surface of said boss communicating with the interior of said container; an inverted cup fitting upon said boss and having an opening registerable with said boss opening by the rotation of said cup on said boss; and a spout provided upon said cup communicating with said cup opening, the axis of said spout being inclined upwardly at an acute angle with the axis of said boss, so that when said cup is turned to close said boss hole, said spout will lie across the axis of said container and close to the top of said container and when turned a half revolution said spout will be tilted upwardly and outwardly and will communicate through said cup hole with the interior of said container.

7. In a swingspout pouring device for a container: a valve having a boss mounted upon the top of said container with its axis inclined from a normal to said top; a cup mounted upon said boss to form a snug fit therewith and to rotate thereon so that openings provided in said boss and said cup may be brought into or out of registry to open or close said valve; and a spout mounted on said cup the axis of said spout forming an upward acute angle with the axis of said cup, said spout being disposed outwardly and upwardly when said valve is open and substantially horizontally and adjacent to the top of said container when said valve is closed.

In testimony whereof, I have hereunto set my hand at Los Angeles, California, this 8th day of February, 1923.

OZRO N. WISWELL.
